U.S. Appl. No. 61/830,477, filed Jun. 3, 2013.

Primary Examiner — Abraham Bahta(57) **CLAIM**

The ornamental design for a storage bag, as shown and described.

DESCRIPTION

FIG. 1 is a front view of a storage bag showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front view of another embodiment of a storage bag showing our new design;

FIG. 8 is a rear view thereof;

FIG. 9 is a left side view thereof;

FIG. 10 is a right side view thereof;

FIG. 11 is a top view thereof; and,

FIG. 12 is a bottom view thereof.

The shade lines in the Figures show transparency or translucency.

The broken lines show portions of the storage bag that form no part of the claimed design.

The dot-dash lines show no specific length and form no part of the claimed design.
